(57) **ABSTRACT**

A new Petchoa plant particularly distinguished by having
large white flowers and an upright habit, is disclosed.

1 Drawing Sheet

1

Genus and species: *Petunia x Calibrachoa* hybrid.
Variety denomination: 'KLECA23830'.

BACKGROUND OF THE NEW PLANT

The present invention comprises a new and distinct variety of *Petunia x Calibrachoa* hybrid, commonly known as Petchoa, and hereinafter referred to by the variety name 'KLECA23830'. 'KLECA23830' originated from a controlled-cross between the female variety SuperCal® Blushing Pink (also known as 'SAKPXC008', U.S. Plant Pat. No. 25,418) and the male *Calibrachoa* variety 'KLECA12235' (U.S. Plant Pat. No. 25,287).

In August 2017, the female variety SuperCal® Blushing Pink and the male variety 'KLECA12235' were crossed via a controlled-cross in Stuttgart, Germany and seeds were obtained. The seeds were sown and plants were grown for evaluation. A plant line was selected in May 2018 and subsequently named 'KLECA23830'. 'KLECA23830' was first vegetatively propagated by cuttings in Stuttgart, Germany. 'KLECA23830' was found to reproduce true to type in successive generations of asexual propagation via cuttings.

SUMMARY

The following are the most outstanding and distinguishing characteristics of this new variety when grown under normal horticultural practices in Stuttgart, Germany.

1. Large, white flowers; and
2. Upright plant habit.

DESCRIPTION OF THE PHOTOGRAPH

This new Petchoa plant is illustrated by the accompanying photograph which shows a close-up of the whole plant. The

2

photograph is of a 14-week-old-plant grown indoors in Stuttgart, Germany in May 2022. The colors shown are as true as can be reasonably obtained by conventional photographic procedures.

DESCRIPTION OF THE NEW VARIETY

The following detailed descriptions set forth the distinctive characteristics of 'KLECA23830'. The data which define these characteristics were collected from asexual reproductions carried out in Stuttgart, Germany. Data was collected on 8-week old plants after transplant in Stuttgart, Germany. Color references are to The R.H.S. Colour Chart of The Royal Horticultural Society of London (R.H.S.), 5th edition (2007).

Classification:

Family.—Solanaceae.

Species.—*Petunia x Calibrachoa* hybrid.

Common name.—Petchoa.

Parentage:

Female.—SuperCal® Blushing Pink (also known as 'SAKPXC008', U.S. Plant Pat. No. 25,418).

Male.—'KLECA12235' (U.S. Plant Pat. No. 25,287).

Plant description:

Life cycle.—Annual.

Form.—Short lived subshrub.

Habit.—Upright.

Height (from soil line to top of foliage).—17.0 cm.

Spread.—40.0 cm.

Propagation:

Type cuttings.—Tip cuttings.

Time to produce a rooted cutting.—3 weeks.

Stems:

Stem color.—RHS 144B.

Pubescence.—Present.

4

COMPARISON WITH PARENTAL LINES AND KNOWN VARIETY

TABLE 1

Comparison with Parental Lines				
40	Trait	Variety	Female parent	Male parent
		‘KLECA23830’	SuperCal ® Blushing Pink	‘KLECA1225’
Flower color		RHS NN155C + 70A	RHS 65C	RHS NN155D
Growth habit		Upright	Very upright	Very flat

TABLE 2

Comparison with Similar Variety		
Trait	Variety	SuperCal ® Cherry Improved
Flower color	RHS NN155C + 70A	Red-purple RHS N57

What is claimed is:

60 1. A new and distinct *Petunia-Calibrachoa* hybrid plant
named 'KLECA23830' as shown and described herein.
